UNITED STATES PATENT OFFICE.

JOSEPH JOHNSON AND CARYL D. HASKINS, OF LYNN, MASSACHUSETTS, ASSIGNORS TO THE GENERAL ELECTRIC COMPANY, OF NEW YORK.

FIELD-MAGNET COIL AND METHOD OF MANUFACTURING SAME.

SPECIFICATION forming part of Letters Patent No. 508,620, dated November 14, 1893.

Application filed May 2, 1893. Serial No. 472,814. (No model.)

To all whom it may concern:

Be it known that we, JOSEPH JOHNSON and CARYL D. HASKINS, citizens of the United States, and residents of Lynn, in the county of Essex and State of Massachusetts, have made certain new and useful Improvements in Field-Magnet Coils and Methods of Manufacturing the Same, of which the following is a specification.

10 Our invention relates to field coils and to methods for their manufacture, and has for its object to provide a simple form of such coil easily constructed and of small cost. To this end we construct such coils of a single 15 piece of copper cast or stamped into suitable form and then provided with saw cuts into which insulation may be inserted, as illustrated and described more fully hereinafter.

In the accompanying drawings hereby referred to and made part of this specification, like letters refer to like parts throughout; and therein—

20 Figure 1 is a front elevation of a field-magnet coil of one turn made according to our invention. Fig. 2 is a side elevation of the parts shown in Fig. 1, and Figs. 3 and 4 are similar views of a modified form used where two coils or more are desired.

25 Referring by letter, A is the body of the coil, which is substantially a ring or tube of any desired cross-section; B is an extension or tongue forming a terminal at C and provided with holes D, D, into which the wires of the circuit may be inserted and secured by 30 the set-screws S, S. A' is a similar portion of the coil made in reverse shape from the part A and having a similar tongue or projection B', similar terminals C', and holes D' D' for securing the circuit wires. It will be observed that the parts thus described are made 35 right and left handed and that only two castings are necessary in the form shown, which are secured together at E by the countersunk screws T T', Fig. 1.

40 After the parts are secured into position shown, slots X, X' are cut with a hack-saw or milling tool, thus interrupting the continuity of the ring; into these slots suitable insulation, as a sheet of mica or hard fiber, may 45 be inserted, or the parts may be separated merely by the air space. The arrows show

the course of the current in the different views. As thus described, two castings are necessary to make the one turn; but in the modified form of coil shown in Figs. 3 and 4, 55 the castings on the right and left respectively of the part G connecting them are interchangeable. In this form lugs or tongues F, F' are provided on diagonally opposite corners of the casting and upon assembling the 60 parts of the coil as many turns as may be desired may be formed by connecting the lugs F, F' by means of a conducting piece G, as fully shown in Fig. 3. As in the case of Figs. 1 and 2, after the slots Y, Y', are cut any suitable insulation may be inserted or not, as may be desired. The coils thus made, as will be seen, are adapted to carry very heavy currents and are of small cost.

65 The particular construction shown and described is that which we have found desirable for electric meters; but we do not mean to limit our invention to this alone, as it is manifest that it may be extended to other forms of field coils, where the continuity of the tube 70 or ring is interrupted by a spiral slot, such a form being well adapted for series coils in a dynamo electric machine.

75 Having thus described our invention, what we claim as new, and wish to protect by Letters Patent of the United States, is—

80 1. The method of constructing field-magnet coils, which consists in forming a ring provided with terminals and then breaking the continuity of the ring by a cut, substantially 85 as described.

85 2. The method of constructing field-magnet coils, which consists in forming a ring provided with terminals, breaking the continuity of the ring by a cut, and then inserting insulation into the cut, substantially 90 as described.

95 3. The method of constructing field-magnet coils, which consists in casting a copper ring of suitable cross section provided with a lug or tongue to be used as a terminal, and then breaking the continuity of the ring by a cut.

100 4. The method of constructing field-magnet coils, which consists in casting a copper ring of suitable cross section provided with a lug or tongue to be used as a terminal, breaking the continuity of the ring by a cut, and then inserting insulation into the cut.

5. As an article of manufacture, a coil for a field-magnet, composed of a ring or tube the continuity of which is interrupted by a slot.
- 5 6. As an article of manufacture, a coil for a field-magnet, composed of a ring the continuity of which is interrupted by a slot with insulation therein.
7. As an article of manufacture, a field-magnet coil, consisting of a ring of cast copper, the continuity of which is interrupted by a slot or slots, the ring being provided with lugs adapted to serve as terminals.
- 10 8. As an article of manufacture, field-magnet coils for an electric meter, adapted to be

used interchangeably when more than one turn in the coil is required, consisting of rings of copper of suitable cross section, the continuity of which is interrupted by slots as Y, Y', and provided with diagonally opposite ~~20~~ lugs, F, F', adapted to serve as terminals for the coils.

In witness whereof we have hereunto set our hands this 18th day of April, 1893.

JOSEPH JOHNSON.
CARYL D. HASKINS.
